UNITED STATES PATENT OFFICE.

FRANCIS J. McGOWEN AND KARL W. THALHAMMER, OF LOS ANGELES, CALIFORNIA,
ASSIGNORS OF FIVE-TWELFTHS TO SAID McGOWEN, ONE-FOURTH TO SAID THAL-
HAMMER, AND ONE-THIRD TO IDA R. FORBES, OF LOS ANGELES, CALIFORNIA.

TELEPHONE SIGNAL AND RECORDER.

1,224,185.

Specification of Letters Patent.

Patented May 1, 1917.

Application filed April 22, 1915. Serial No. 23,000.

To all whom it may concern:

Be it known that we, FRANCIS J. McGOWEN, a citizen of the United States, and KARL W. THALHAMMER, a subject of the Emperor of Austria, both residing at Los Angeles, in the county of Los Angeles and State of California, have invented a new and useful Telephone Signal and Recorder, of which the following is a specification.

10 This invention relates to means for enabling a call or message to be received at a telephone subscriber's station in the absence of the party called, and the main object of the present invention is to provide means 15 for this purpose which will be self contained, so that it will be capable of operation independently of the subscriber's telephone set.

Another object of the invention is to provide 20 for sending an "out" signal over the calling line and immediately thereafter putting such calling line in connection with a recording device, to enable a message to be recorded.

25 The accompanying drawings illustrate our invention, and referring thereto:

Figure 1 is a plan view of the device, the cover being removed.

Fig. 2 is a side elevation of the telephone 30 line relay, and the locking and resetting means therefor.

Fig. 3 is a vertical section on line 3—3 in Fig. 1.

Fig. 4 is a vertical section on line 4—4 35 in Fig. 1.

Fig. 5 is a side elevation of a supplementary circuit closing means for the signal controlling device.

The present invention comprises line relay 40 means for receiving a calling current from a telephone line, signal means set in operation by such line relay means, for sending back to the calling station a signal current indicating that the party called is out, and 45 that a message will be automatically received; and means also set in operation under control of the line relay and of the signal means, for recording a message received from the line.

50 All of the above-mentioned instrumentalities are preferably mounted in a case 1, which may be provided with a false bottom 1' below which are contained a battery 2 and a condenser 3. Case 1 is provided with

terminals 4 and 5 for connection to a telephone line; with terminals 6 and 7 for battery 2; with terminals 8 and 9 for wires leading to a telephone receiver operating in connection with a recording instrument; and with terminals 10 and 11 for wires leading to the motor for such recording instrument.

A line relay 12 mounted in the case 1, is provided with armature lever 13, having armature 13', retracting spring 14 and back stop 15, said armature lever carrying an insulating block 16 which is adapted to engage contact springs 17 and 18 on an insulating support 19 and to force such contact springs against contact pins 21 on springs 22 and 23, respectively, also mounted on support 19, said pins 21 extending through holes 24 in said support. Locking means are provided for holding armature lever 13 in operated position, said means comprising a locking lever 25 formed as an armature for a resetting magnet 26, and having a shoulder or hook 28 adapted to engage the outer end of armature lever 13 to hold the same down; a retracting spring 30 for said lever 25 and 80 a back stop 31 serving to normally hold lever 25 in position with an inclined face 32 at its upper end directly below the outer end of lever 13, so that when lever 13 descends it will push lever 25 forward, by engagement 75 with said inclined face, and permit said lever to catch under shoulder 28.

Resetting magnet 26 also operates to control the recording means, the armature 25 of said magnet being provided with an insulating projection 34 adapted, when the armature is attracted, to engage spring-contacts 35 and 36 on an insulating support 33, and to press the same into contact, respectively, with pins 37 on spring contacts 38 and 39, 90 connected to control the recorder, as herein-after described.

Means are provided, operating under control of line relay 12, for sending back an "out" signal over the line. For this purpose 100 we use a signal transmitter independent of the subscriber's instrument. Any means for producing signal impulses in the line may be used for this purpose, but we prefer to use a telephone transmitter 40 connected to the line, a bell or audible signal device 41, located in position to deliver sound waves to said transmitter, and circuit controlling 105

means for energizing said bell. Said circuit controlling means comprises a circuit closing metal sleeve 48 mounted on and insulated from a shaft 49, and co-operating with two contact springs or brushes 53 and 53' to control the circuit of bell 41, said sleeve being cut away at 55 to normally break the connection. Shaft 49 is mounted in bearing member 49' and is operated step by step by pawl 51 on an armature lever 44, operated by magnet 47, which is provided with retracting springs 46 and with back stop 45, and back contact 45'. Circuit closer shaft 49 also carries an eccentric or cam 56 adapted to engage a lever 57 and to press a contact 58 on said lever against a fixed contact 59, to close circuit to the operating magnet 47 independently of the armature of line relay 12. Lever 57 also carries an insulating projection 60 adapted to engage a spring contact 61 to press the same into contact with a spring contact 62 to close contact with the resetting magnet 26 aforesaid. A spring 57' returns lever 57 to normal position.

The telephonic recorder used in connection with this apparatus may be of any suitable type, comprising for example, a motor 63, driving a record cylinder 64 on which record is made by a recording means 65 operated by telephonic receiving means 66, this recording instrument being also provided with the usual means for reproducing the sound represented by the record.

The circuit connections shown in Fig. 1 are suitable for use with a "central energy" system and are as follows: The telephone line, indicated at 68, 69 is connected in the usual manner to a subscriber's instrument, including receiver 70, transmitter 71, hook lever 72, call bell 73 and the usual condensers and inductance means. The wires 68 and 69 of the telephone line are also connected respectively, by taps 68' and 69', to terminals 4 and 5. Line relay magnet 12 is connected across the telephone line, in shunt with the subscriber's instrument, through a connection including a cut-out switch 74 and condenser 3, this connection leading from terminal 4 by wire 77 to switch 74 and from said switch by wire 75 to condenser 3 and thence by wire 75' to relay 12, whence wire 76 leads to terminal 5. The "out" signal transmitter 40 is connected in a normally open branch, across the telephone line, leading from wire 75 to wire 80 to contact 18, and from contact 23 through wire 81 to said transmitter and thence by wire 82 to line terminal 5. Another normally open branch leads from wire 75, by wires 80 and 84 to contact 35, and from contact 38 through wire 86 to terminal 8 for the telephone of the recorder, said telephone being connected by wires 88 and 89 to terminals 8 and 9. From terminal 9 a wire 90 leads to line terminal 5. A wire 85 leads from wire

86 to magnet 26 and from said magnet a wire 87 leads to wire 76 aforesaid. Battery 2 is connected by wires 54, 54' to the terminals 6 and 7. A wire 91 leads from battery terminal 6 to a wire 92 connected to contact 61, the contact 62 being connected to wire 93 leading to wire 87 connected to magnet 26, and the wire 86 connected by wire 85 to the other side of said magnet is connected to wire 94, leading to battery terminal 7. Magnet 26 is thus connected in a normally open circuit with the battery, through contacts 61 and 62, and in a normally open branch from the line, through contacts 35 and 36. The motor 63 of the telephonic recorder is connected by wires 96, 97 and 98 with the terminals 10 and 11 and with an electric supply circuit 100, 101. Terminals 10 and 11 are connected by wires 102 and 103 to the contacts 36 and 39 controlled by magnet 26. Circuit for the signal controlling magnet 47 leads from battery terminal 6 through wire 91 to contact 22, and from contact 17 by wire 106 to magnet 47, whence a wire 107 leads to back contact 45', the armature lever 44 being connected to wire 94 leading to battery terminal 7. A supplementary circuit for this magnet independent of the contacts 17 and 22, leads from wire 91, by wire 95 to contact 59 for lever 57, said lever being connected by wire 111 to wire 106. Bell 41 is included in a branch controlled by circuit closer 48, said branch leading from battery wire 91 through wire 114 to bell 41 and from said bell by wire 113 to brush 53, and from brush 53' by wire 115 to wire 94 leading back to battery.

A switch or push button 118 may be provided for closing a branch connection 119, 120, between wires 77 and 86, and a branch connection 121, 122 between wires 102 and 103, so that when switch 74 is open and the subscriber is using his telephone in the usual manner, he may, by closing switch 118 put the recorder 66 in connection with the line and start it in operation to take down the conversation carried on over the line. A condenser 130 may be included in this connection.

The operation is as follows: When the device is not needed, the switch 74 is opened, and the telephone line is then in normal condition in all respects, calls being received and answered in usual manner. In case, however, the subscriber wishes to receive calls automatically, for example, while he is absent from the office or room in which the telephone is located, he will close switch 74 and the device is then in condition for automatic reception and record of messages. If now a party calls the subscriber, either automatically or through a central operator, the calling current, being an alternating current, passes through wire 77, switch 74, wire 75, condenser 3, wire 75', relay 12 and wire 130

76 to line terminal 5. Energization of relay 12 causes its armature lever 13 to descend, said lever being caught by detent hook 28 and held down in position to cause insulating block 16 to press contacts 17 and 18 against contacts 22 and 23 respectively. Current then passes from battery 2 through wire 54 to terminal 6, thence by wire 91 to contact 22, and from contact 17 by wire 106 to magnet 47, thence by wire 107 to back contact 45' and from armature 44 through wire 94 to battery terminal 7, wire 54' and the other side of battery. Magnet 47 then attracts its armature, breaking circuit at the back contact, and a vibratory motion of the armature results, the circuit being made and broken at 45' and the pawl 51 on armature lever 44 operates the rotary circuit closer 48 step by step, bringing the metal thereof under brush 53' and closing circuit to the call bell 41, as follows: from battery 2 to wire 91, thence by wire 114 to bell 41, and thence by wire 113 to brush 53, through sleeve 48, brush 53' and wire 115 to wire 94 and battery terminal 7. Bell 41 then rings continuously until member 48 makes a complete revolution, bringing the insulating portion 55 under contact 53'. The sound waves set up by the operation of bell 41, operate through the transmitter 40 to send a signal to the line, current passing from line terminal 4 through wires 77 and 80 and contacts 18 and 23, closed at this time by operation of armature lever 13, thence by wire 81 to transmitter 40 and from the transmitter by wire 82 to line terminal 5. The impulses thus transmitted to the line notify the calling party, or central, as the case may be, that the called party is out and that a message will be automatically received. The character of this signal is such that it may be readily distinguished from a "busy" signal. In case the call comes from central, the operator will notify the calling party that the called party is out, but that he may leave a message. In case the call is directly from a calling party, he will recognize the response through the line as notification to the same effect. He will then speak his message into his transmitter, and the message thus transmitted over the line will be recorded as hereinafter explained. At or about the time that circuit closer 48 has nearly completed its movement, the cam 56 on shaft 49 of said circuit closer operates lever 57 to close contact at 61, 62 and current then flows from battery terminal 6, through wires 91 and 92 to contact 61, and from contact 62 by wire 93 to magnet 26, thence by wires 85 and 94 to battery terminal 7. Magnet 26 then draws armature 25 to close contact at 35, 38 and also at 36, 39. This operation of armature 25 also releases hook 28 from armature lever 13 and allows said lever to return to normal position. This return of lever 13 to normal position does not, by breaking contact at 17 and 18, interrupt the circuit for magnet 47, for the reason that contact pin 58 on lever 57 at this time closes with contact 59 to establish a supplementary circuit for said magnet, as follows: from wire 91 through wire 95 to contact 59 and from contact lever 57 by wire 111 to wire 106 leading to magnet 47. Magnet 47 therefore continues to operate until the revolution of shaft 49 is completed, when cam 56 allows lever 57 to move to separate contacts 58, 59. The signal controlling means are then restored to normal position and the operation of call bell 41 is stopped. Opening of contacts 61 and 62 does not, however, cause de-energization of magnet 26 for the reason that said magnet, when energized by action of battery 2, closes contact at 35, 38 by engagement of insulating projection 34 with contact 35 and thereby establishes a retaining connection for itself, under the control of the line current, as follows: from terminal 4 through wires 77, 75, 80 and 84 to contact 35 and from contact 38 through wires 86 and 85 to magnet 26, thence by wires 87 and 76 to line terminal 5. For a moment the battery 2 and the line battery, at central, are on magnet 26 at the same time, and the connections must of course be such that their effects on the magnet are not in conflict. Magnet 26 is sufficiently sensitive to retain its armature by the action of line current alone, when the battery current is removed by breaking contact at 61, 62, and the closure is therefore maintained at contacts 35 and 38 and also at contacts 36 and 39, as long as there is current on the line, that is, until the calling party "hangs up." Closure at contacts 35, 38 establishes a circuit from the line to the recording telephone as follows: from line terminal 4, through wires 77, 75, 80, and 84, contacts 35 and 38, wires 86 and 88 to telephone receiver 66 and thence by wires 89 and 90 to line terminal 5. This connection is in shunt with the magnet 26 and the latter must be of sufficient impedance to enable talking current to pass effectively to the telephone receiver 66. At the same time, closure of contacts 36, 39 establishes energizing connection for motor 63 of the recording instrument, from power line 100 through wire 98, motor 63, wires 96, and 102, contacts 36 and 39, wires 103 and 97 and resistance 117 to power line 101. The recording cylinder is thereby started in motion as soon as the recording telephone receiver 66 is put in connection with the line, and immediately after the operation of the signal transmitting means 41 and 40. The message spoken by the calling party after he has been notified that a message will be received, is then recorded on the cylinder 64. When his message is completed and he hangs up his receiver, current ceases on the 130

line and magnet 26 releases its armature which then breaks circuit at 35, 38 and at 36, 39, thus restoring the normal conditions.

It will be noted that except at the time a 5 call is being received the only connection to the line is through condenser 3, so that the normal operation of the line is not interfered with.

What we claim is:

- 10 1. In a telephone signal and recorder, the combination with a telephone line and a subscriber's instrument permanently connected thereto, of a branch line connected to the telephone line and including a normally open switch and a relay magnet, a signal transmitting means, independent of the subscriber's instrument and normally disconnected from the telephone line and from said branch line, means controlled by 15 said relay magnet for operating said signal transmitting means for a predetermined time, and means controlled by said relay magnet for putting said signal transmitting means in connection with said telephone line 20 for sending a signal back over said line.
- 25 2. In a telephone signal and recorder, the combination with a telephone line and a subscriber's instrument permanently connected thereto, of a branch line connected to said telephone line and including a normally open switch, a condenser and a relay magnet, a signal transmitting means, independent of the subscriber's instrument and normally disconnected from the said telephone line and from said branch line, means controlled by 30 said relay magnet for operating said signal transmitting means for a predetermined time, and means controlled by said relay magnet for putting said signal transmitting means in connection with said telephone line 35 for sending signals back over the telephone line.
- 40 3. In a telephone signal and recorder, the combination with a telephone line and a subscriber's instrument connected thereto, of a branch line connected to said telephone line and including a normally open switch and a relay magnet, a telephone transmitter normally disconnected from the telephone line, means controlled by 45 said relay magnet for putting said transmitter in connection with said telephone line, an electric bell adjacent to said telephone transmitter, an operating circuit therefor including a source of current and a normally open circuit closer and means controlled by said relay magnet for closing said circuit closer for a predetermined time on operation of said relay magnet.
- 50 60 4. In a telephone signal and recorder, the combination with a telephone line and a subscriber's instrument permanently connected thereto, of a branch from said telephone line including a normally open switch and a relay magnet, a telephone receiver and a

recorder for recording the messages received by said receiver, means controlled by said relay magnet for operating said recorder and for putting said telephone receiver in connection with said telephone line, a second switch and circuit connections controlled thereby for energizing said recorder operating means and for putting the said telephone receiver in connection with the line, independently of the first named switch, and independently of the operation of said relay magnet.

5. In a telephone signal and recorder, the combination with a telephone line and a subscriber's instrument connected thereto, of a branch connection from said telephone line, including a relay magnet, an armature for said magnet, locking means for holding said armature in operated position, means for restoring said armature to normal position when released from said locking means, a signal transmitting means independent of the subscriber's instrument, means controlled by said armature for operating said signal transmitting means for a predetermined time, releasing means controlled by the operation of said signal operating means, to release said locking means on completion of operation of the signal transmitting means, means controlled by the said armature for putting said signal transmitting means in connection with the telephone line, a phonographic recording device and means controlled by said releasing means to put said phonographic recording device in connection with the telephone line on operation of said releasing means.

6. In a telephone signal and recorder, the combination with a telephone line, of a branch circuit connected thereto and including a relay magnet, an armature for said magnet, provided with means for restoring it to normal position, a locking armature provided with means for engaging the armature of said relay magnet to hold the same in operated position and with means for restoring said locking armature to normal position to engage the relay magnet armature, a releasing magnet adapted to operate said locking armature to release the relay magnet armature, signaling means, means controlled by said relay magnet armature for operating said signaling means and for putting said signaling means in connection with the telephone line, and means controlled by the operation of said signaling means for energizing said releasing magnet on completion of such operation.

7. In a telephone signal and recorder, the combination with a telephone line, of a relay responsive to current in said line, a signal means controlled by said relay to signal back over the line, a telephonic recording means, and means controlled by said relay to put the telephonic recording means in

connection with the line, and to interrupt the connection of the telephonic recording means with the telephone line when current ceases on the said line.

- 5 8. In a telephone signal and recorder, the combination with a telephone line, of a relay magnet responsive to current on said line, a signal means, a signal controlling means controlled by said relay and adapted
- 10 to operate said signal means for a predetermined time, means controlled by said relay to put said signal means in communication with the telephone line, to signal back over the line, a telephonic recording

device, electromagnetic means controlled by 15 said signal means to put the telephonic recording device in connection with the telephone line, and a connection from said electromagnetic means to the line, closed by operation of said electromagnetic means, so 20 that the telephonic recording means will be maintained in communication with the line while current is maintained in the line.

In testimony whereof we have hereunto set our hands, at Los Angeles, California, 25 this 14th day of April 1915.

FRANCIS J. McGOWEN.
KARL W. THALHAMMER.
